UNITED STATES PATENT OFFICE.

JOHN L. BOARDMAN, OF BUTTE, MONTANA.

REFILLABLE REGENERATOR.

Application filed June 18, 1921. Serial No. 478,618.

To all whom it may concern:

Be it known that I, JOHN L. BOARDMAN, a citizen of the United States, residing at Butte, in the county of Silver Bow and State of Montana, have invented certain new and useful Improvements in Refillable Regenerators, of which the following is a specification.

This invention relates to refillable regenerators or containers for holding material which will absorb CO_2 and particularly to refillable regenerators for use with self contained oxygen breathing apparatus.

An object of the invention is to provide a regenerator which will permit the ready removal of the absorbent material. A further object is to provide a regenerator which exposes a large surface to the air passing therethrough and which offers but little resistance to the passage of the air. A further object is to provide a regenerator which eliminates all danger of short circuits, i. e., passage of air through the regenerator without contacting with the absorbent material.

One particular embodiment of my invention which is particularly adapted for use with the "Paul" type of breathing apparatus is illustrated in the accompanying drawings, in which—

Figure 1 is a perspective view of the regenerator;

Fig. 2 is a vertical section through the regenerator, taken on line 2—2 of Fig. 3;

Fig. 3 is a vertical section taken on line 3—3 of Fig. 2;

Fig. 4 is a horizontal section taken on a plane passing through the upper part of the container, as indicated by line 4—4 of Fig. 2;

Fig. 5 is an elevation of one of the partitions used in the regenerator.

The regenerator consists of a casing or canister which is formed of suitable non-rusting sheet metal and comprises side walls 1, 1, end walls 2, 2, top 3 and bottom 4.

The terms "side and end walls, top and bottom" are used merely for convenience of description as the regenerator when in use may occupy other positions than that illustrated in Fig. 1.

The canister is divided by means of foraminous partitions 5 into air compartments 6, 6' and an absorbent material compartment 7. Considering the regenerator arranged as shown in the drawings, these partitions and the compartments formed there-

by are vertically arranged and the term "vertical" as used in the specification and claims is to be construed as defining the location of these or other elements when the regenerator is positioned as shown in the drawings.

To prevent short circuiting of the air when the canister is lying on its side and the compartment 7 is not completely filled with absorbent material, imperforate baffles 8, 8 are provided at the sides of the partitions 5. If desired the baffles may extend around the entire periphery of partitions 5 but I find that such a construction is seldom necessary.

One corner of partition 5 which forms a wall of compartment 6 is cut away as at 5' and through the opening thus formed the compartment communicates with a laterally extending passage 9 which overlies a portion of chamber 7. The upper wall of passage 9 is formed by the top 3 and the other walls are formed by a deflector plate 10 which is attached to the casing and to the partition. At the opposite side of the casing a similar passage 9' communicates with chamber 6' and is formed by deflector plate 10' and top 3.

The top 3 is provided with a filling opening which communicates with chamber 7 and which is closed by filling plug 12 and a leather or other suitable washer 13. Top 3 is also provided with openings communicating with passages 9 and 9' respectively, and these openings are provided with suitable connections 14, 14' respectively, to which the inhalation and exhalation tubes may be attached. The direction in which exhaled air passes through the container is immaterial and therefore the inhalation tube may be attached at either 14 or 14'.

Braces 15 are located between the screen partitions 5 and the adjacent wall 1 of the canister. Dependent upon convenience in assembling, braces 15 may be attached either to the partition 5 or to the wall 1, and both arrangements are illustrated in Fig. 4.

The canister body may be formed in any suitable way according to known methods of manufacture of sheet metal cans or vessels. The various elements are formed from brass or other non-rusting material and all joints between the elements of the device are soldered or otherwise hermetically sealed.

In use the regeneration material or CO_2

absorbent is filled into compartment 7 until the compartment is substantially full. Filling plug 12 is then applied to form an air-tight closure. The canister is placed in the apparatus with either connection 14 or 14' uppermost and the inhalation and exhalation tubes are connected in the proper manner. The exhaled breath of the wearer enters through one connection, as 14 and passes through the passage 9 into compartment 6. From compartment 6 the air travels through the foraminous partition 5, through the absorbent material and the other partition 5 into compartment 6'. From thence the regenerated air passes through passage 9' and connection 14' to the inhalation tube of the apparatus.

The device is simple in construction, efficient in the absorption of CO₂, comparatively safe in operation and is easily emptied and recharged.

It is to be understood that my invention is not limited to the specific embodiment above described but that various changes in the elements, their relative size, shape and location may be made within the scope of my invention.

I claim—

1. In a refillable regenerator, a casing, partitions spaced from and substantially parallel to the opposite walls of said casing and forming therewith air compartments and an intermediate compartment for holding regenerating material, each of said partitions comprising a foraminous section and imperforate baffle sections.

2. A refillable regenerator comprising a casing, a pair of foraminous partitions which with the opposite walls of said casing divide said chamber into two air compartments and an intermediate material holding compartment, an opening in the wall of said casing through which material may be introduced into said intermediate compartment, and a pair of openings in the wall of said casing, each of said openings communicating with one of said air compartments.

3. A regenerator comprising a casing provided with air inlet and outlet openings, a pair of foraminous partitions extending across the path of the air current through said casing and dividing said casing into two air chambers and a chamber for holding regenerating material, and a pair of passages extending along one wall of said casing, each of said passages establishing communication between one of said casing openings and one of said air chambers.

4. A refillable regenerator comprising a casing, vertical foraminous partitions cooperating with the side walls of the casing to form air chambers and a chamber for holding regenerative material, passages

through said partitions and extending from the respective air chambers along the top of the casing, openings in the top of said casing communicating with the respective passages and provided with means for attaching inhalation and exhalation tubes, an opening in the top communicating with the material holding chamber and a closure for said last mentioned opening.

5. A regenerator comprising a casing, vertical partitions dividing said casing into two air compartments and an intermediate compartment for holding regenerative material, plates connected to said partitions and cooperating with the top of the casing to form passages communicating respectively with the two air compartments, openings in the top of the casing and communicating respectively with the three compartments, means for attaching inhalation and exhalation tubes to the openings leading to said air compartments and a closure for the opening into said intermediate compartment.

6. A regenerator comprising a casing, vertical foraminous partitions adjacent the side walls of said casing, braces between said partitions and the adjacent casing wall and imperforate baffles at the periphery of said foraminous partitions.

7. A regenerator comprising a casing, vertical foraminous partitions cooperating with the side walls of said casing to form air compartments adjacent said side walls and an intermediate compartment for holding regenerative material, an opening in the top of said casing and communicating with said material holding compartment, a closure for said opening, means on the top of said casing for attaching inhalation and exhalation tubes and passages leading from said means to the respective air compartments.

8. A refillable regenerator comprising a casing, a pair of foraminous partitions dividing said casing into air compartments and an intermediate compartment for holding regenerating material, outlets arranged in one wall of said casing and in alignment with said material holding compartment, one of said outlets opening directly into said material holding compartment, a pair of passages extending along said wall and across said material holding compartment, one of said passages establishing communication between one of said outlets and one of said air compartments and the other of said passages establishing communication between another of said outlets and the other air compartment, and a closure for said material holding compartment outlet.

In testimony whereof, I affix my signature.

JOHN L. BOARDMAN.
